UNITED STATES PATENT OFFICE

CHARLES A. MEALY, OF WEST BARRINGTON, RHODE ISLAND, ASSIGNOR TO THE HADLEY COMPANY, INC., OF PROVIDENCE, RHODE ISLAND, A CORPORATION OF RHODE ISLAND

FLEXIBLE BRACELET

Application filed January 7, 1931. Serial No. 507,165.

This invention relates to bracelets for personal wear, and has for its principal object the provision of a flexible bracelet in which a series of parallel, transverse strips of thin wood or other veneers are mounted upon a longitudinal band of fabric or other flexible backing material with the opposite edges of the veneer strips preferably covered and protected by binding elements. A bracelet constructed in accordance with this invention may be used as an ordinary wrist band or may be suitably connected to a wrist watch or other article of jewelry; and common forms of separable clasps or extensible connectors may be provided to permit the application of the bracelet to the wrist of the wearer.

By this simple and economical mode of manufacture, various types of wood veneers, or thin and narrow strips of other attractive and ornamental materials may be combined with metal, leather and/or other relatively inexpensive fabrics to produce a strong, durable and comfortable bracelet of unique and pleasing appearance. The particular features of the improved bracelet are set forth in the following description of preferred species of the invention and are pointed out in the appended claims, it being understood that the structural details of the article may be varied to suit particular purposes without departing from the essence of the invention.

Recommended embodiments of the invention are illustrated in the accompanying drawings, in which:

Fig. 1 is a top view of a portion of a watch bracelet illustrating a preferred form of construction;

Fig. 2 is a fragmentary bottom view of the bracelet;

Fig. 3 is an enlarged transverse section of Fig. 2;

Fig. 4 is a fragmentary top view of a modified construction;

Fig. 5 is a transverse section of Fig. 4; and

Fig. 6 is a detail view of one of the metal binding members forming part of the preferred construction, prior to its application to the bracelet.

In the particular embodiment chosen for the purpose of illustration in Figs. 1 to 3, the improved bracelet comprises a flexible, longitudinal backing which assumes the tensile strain of the bracelet, a plurality of parallel, juxtaposed wooden strips or veneers 7 mounted upon the backing, and a series of transverse metal strips 8 extending across the bottom of the backing and having their opposite ends folded over the bracelet edges and crimped downwardly upon the end portions of the respective veneers, as at 9. The backing may be formed of any suitably strong and flexible material such as textile fabric, leather, mesh or the like, and in the form shown consists of superposed fabric strips 10 and 11 which may be adhesively united if desired.

The veneers 7 are preferably cemented or otherwise secured to the upper face 10 of the backing before the metal binders 8 are applied, and it will be observed that these metal reinforcements not only provide a smooth, rounded and wear-resisting edge binding of attractive appearance, but also assist in retaining the veneers in assembled relation. The metal ends 9 preferably register with end portions of the respective veneers and the central or bottom portions of the strips 8 are preferably cut away at their opposite sides to provide spaces or openings 12 at the under side of the bracelet, thereby affording adequate flexibility of the completed structure.

It is thus apparent that the body of the bracelet, consisting of the flexible backing and the parallel transverse veneers, may be formed as a unitary band or bracelet section, and that the metal binding strips may be applied to the band by hand or by suitable

machinery; and it will be understood that the backing may consist merely of a single strip of flexible sheet material or of the two or more plies, as desired; and that the veneers may be narrow strips of bone, mother of pearl or other appropriate decorative substances, as well as of wood.

A bracelet band thus constructed may be attached to a wrist watch 13 by means of a suitable connecting member 14, or may be associated with other articles of jewelry or equipped with appropriate clasps or connectors for securing the band about the wrist of the wearer. Such accessories are, however, not essential to the present invention which pertains exclusively to the improved construction of the band section of the bracelet.

A modified construction falling within the purview of this invention is illustrated in Figs. 4 and 5 wherein the bottom layer 15 of the backing consists of a longitudinal piece of leather which is wider than the veneers 7 and the adjacent, primary backing strip 8 and which has its margins 16 folded over the ends of the veneers and secured by parallel lines of stitching 17 passing through the hemmed edges of the leather, the end portions of the strips 7 and the backing. It is obvious that the intermediate backing piece 8 may be omitted in this form as well as in the previous embodiment, without materially weakening the structure; but this strip of fabric is preferably employed as a mounting strip to which the veneers are adhesively affixed in proper relation before applying the remaining elements to complete the bracelet band. Hence the leather strip 15 may constitute a binder which supplements or reinforces the backing strip 8; or it may serve as a unitary backing member and edge binder, to which the veneers are directly affixed.

A bracelet having a flexible band section or wrist-encircling portion constructed as above described is simple and economical to manufacture, yet furnishes an attractive, durable and comfortable article of jewelry whose outer exposed face has the rich and ornamental appearance of a more costly bracelet. The relatively fragile or weak veneers are relieved of tensile strain by the backing strip and their end portions are protected against damage or wear by the edge binding which also affords a pleasing contrast of texture and color along the sides of the bracelet. As above indicated, the structural details of the bracelet may be modified for particular uses within the scope of the appended claims.

I claim:

1. A bracelet comprising a flexible backing, a series of narrow veneers mounted transversely upon the upper surface of the backing in parallel relation, and edge bindings covering the opposite ends of the veneers.

2. A bracelet comprising a longitudinal backing member of flexible material, a series of narrow veneers secured transversely upon the upper surface of the backing in parallel, juxtaposed relation, and edge bindings folded over the opposite ends of the respective veneers and secured upon the outer faces thereof.

3. A bracelet comprising a longitudinal backing member of flexible material, a series of narrow veneers secured transversely upon the upper surface of the backing in parallel, juxtaposed relation, and binding means extending across the bottom of the backing and over the opposite ends of the respective veneers to reinforce the bracelet and furnish edge bindings at its opposite sides.

4. A bracelet comprising a longitudinal backing member of flexible material, a series of narrow veneers secured transversely upon the upper surface of the backing in parallel, juxtaposed relation, and individual metal binding strips extending across the bottom of the backing and folded over the opposite ends of each of the respective veneers.

5. A bracelet comprising a longitudinal backing strip of textile fabric, a plurality of parallel, juxtaposed veneers cemented transversely upon the upper surface of the backing strip, and a series of transverse metal binding elements extending across the bottom of the backing and having their end portions folded over the opposite ends of the respective veneers and upon the upper faces thereof.

6. A bracelet comprising a longitudinal backing strip of textile fabric, a plurality of parallel, juxtaposed veneers cemented transversely upon the upper surface of the backing strip, and a leather binding strip applied to the bottom of the backing and having its side margins folded over the opposite ends of the veneers and stitched to their upper faces.

7. A bracelet comprising a longitudinal backing of textile fabric, a plurality of thin, narrow wooden strips cemented transversely upon the upper surface of said fabric in parallel, juxtaposed relation, and a series of transverse metal binding strips extending across the bottom of the backing and having their end portions folded over the opposite ends of the respective wooden strips and crimped upon the upper faces thereof, the folded portions of the metal strips substantially registering with the end portions of the wooden strips respectively.

8. A bracelet comprising a longitudinal backing of textile fabric, a plurality of thin, narrow wooden strips cemented transversely upon the upper surface of said fabric in parallel, juxtaposed relation, and a series of transverse metal binding strips extending across the bottom of the backing and having their end portions folded over the opposite

ends of the respective wooden strips and crimped upon the upper faces thereof, the folded portions of the metal strips substantially registering with the end portions of the wooden strips respectively, and the bottom portions of the metal binders being narrower than the ends thereof to provide transverse spaces between adjacent binders at the bottom of the bracelet.

10. Signed by me at Providence, R. I., this 3rd day of January, 1931.

CHARLES A. MEALY.
